UNITED STATES PATENT OFFICE

2,583,449

VENETIAN BLIND

Myron S. Tarnoff, Omaha, Nebr.

Application March 9, 1950, Serial No. 148,546

8 Claims. (Cl. 160—170)

1

This invention relates to novel improvements in the construction of Venetian blinds and has for its primary object to enable the slats of the blind to be completely closed either in a downwardly or upwardly slanted arrangement.

Another important object of this invention is to provide a new and simplified operating means for raising and lowering the slats.

Another important object of this invention is to provide a neater appearing blind and one that is easier to clean and to operate by obviating the need for using conventional tapes, elevator cables and tilting mechanism.

These and ancillary objects and structural features of merit are attained by this invention, the preferred embodiment of which is set forth in the following description and illustrated in the accompanying drawings, wherein:

Figure 1 is a rear elevational view of the blind; Figure 2 is a vertical sectional view with the slats illustrated in a raised position; and

Figure 3 is an exploded fragmentary perspective view of the means for supporting the slats.

In the accompanying drawings, the new type of Venetian blind construction 10 is illustrated and is attached to a window frame 12 by means of brackets 14 and 16 affixed to the top 18 of the frame. The brackets are formed with depending parallel sections 20 and 22 which are provided at their front and rear edges with offset branches 24 and 26. A spring-actuated roller 28 is rotatably journaled between the branches 24 of each of the brackets and hubs 30 and 32 are formed on the opposing ends thereof by spaced sets of plates 34. A guide roller 36 is journaled between the branches 24 of each bracket and operating cables or cords 38 and 40, coiled on the hubs 30 and 32, extend over and travel on the guide roller.

A plurality of vertically spaced and aligned slats 42 form the blind proper and are supported by a pair of transversely spaced vertical collapsible frames 44, which are suspended from the brackets by means of a rod 46 mounted between the lower ends of the sections 20 and 22. The rod 46 is mounted for rotation between the brackets and the lower sections of the brackets possess an inherent resiliency so that the rod is frictionally held against free rotation.

The frame 44 includes adjoining complementary collapsible sections 48 and each section consists of transverse bars 50 having sleeve ends 52 and 54. Parallel sets of links 58 and 59 are formed at their opposing ends with eyes 60 and the eyes receive pins 62 positioned in the sleeve

ends 52 and 54. Spring clips 64 project outwardly from the sleeve ends 54 and include angular companion arms 66 and 68. The arms are formed with apertured vertical sections 70 and laterally projecting ends 72 and 74. The ends 70 are formed on their upper faces with projections or protuberances 76 registerable with openings 78 formed in the ends 72. The rear edges of the slats are anchored between the ends 10 of the arms by means of the projections inserted in the slats. The cords 38 and 40 extend through the openings in the section 70 of the arms and the lower ends thereof are tied upon themselves to form stops 80.

15 In use, the blind is raised and lowered in a fashion similar to a conventional window shade by grasping one of the blinds and pulling the entire blind assembly downwardly. To tilt the blind, so that the slats are slanted upwardly or 20 downwardly, it is necessary to rotate the rod 46 to which the transverse bars 52 of the upper section 48 are secured, either by remote control means attached to the rod or by moving one of the slats.

25 However, since many other modifications and purposes of this invention will become readily apparent to those skilled in the art upon a perusal of the foregoing description, it is to be understood that certain changes in style, size and components may be effected without a departure from the spirit of the invention and within the scope of the appended claims.

Having described the invention, what is claimed as new is:

35 1. A Venetian blind comprising supporting brackets, a spring actuated roller rotatably journaled on said brackets, vertically collapsible and tilttable slats, a collapsible structure supporting said slats including a plurality of vertically spaced, parallel, transverse bars terminating in laterally extending end portions, rigid, vertically extending links spacing said transverse bars and pivotally connected to the end portions thereof, means on alternate of said transverse bars securing slats thereto, a supporting member mounted on said brackets and tiltably securing said collapsible structure thereto, means associated with said roller and the lowermost of said transverse bars whereby the lowermost bar may be moved upwardly to effect the sequential collapsing of said rigid links and consequently decrease the spacing between said bars and slats thus collapsing the slats.

50 2. A Venetian blind comprising supporting brackets, a spring actuated roller rotatably

journaled on said brackets, vertically collapsible and tilttable slats, a collapsible structure supporting said slats including a plurality of vertically spaced, parallel, transverse bars terminating in laterally extending end portions, rigid, vertically extending links spacing said transverse bars and pivotally connected to the end portions thereof, means on alternate of said transverse bars securing slats thereto, a supporting member mounted on said brackets and tiltingly securing said collapsible structure thereto, means associated with said roller and the lowermost of said transverse bars whereby the lowermost bar may be moved upwardly to effect the sequential collapsing of said rigid links and consequently decrease the spacing between said bars and slats thus collapsing the slats, said supporting member comprising a rod frictionally and rotatably mounted on said brackets.

3. A Venetian blind comprising supporting brackets, a spring actuated roller rotatably journaled on said brackets, vertically collapsible and tilttable slats, a collapsible structure supporting said slats including a plurality of vertically spaced, parallel, transverse bars terminating in laterally extending end portions, rigid, vertically extending links spacing said transverse bars and pivotally connected to the end portions thereof, means on alternate of said transverse bars securing slats thereto, a supporting member mounted on said brackets and tiltingly securing said collapsible structure thereto, means associated with said roller and the lowermost of said transverse bars whereby the lowermost bar may be moved upwardly to effect the sequential collapsing of said rigid links and consequently decrease the spacing between said bars and slats thus collapsing the slats, said supporting member comprising a rod frictionally and rotatably mounted on said brackets, said rod having a slotted portion receiving the uppermost of said transverse bars whereby upon rotation of the rod the transverse bars and slats secured thereto will be tilted.

4. A Venetian blind comprising supporting brackets, a spring actuated roller rotatably journaled on said brackets, vertically collapsible and tilttable slats, a collapsible structure supporting said slats including a plurality of vertically spaced, parallel, transverse bars terminating in laterally extending end portions, rigid, vertically extending links spacing said transverse bars and pivotally connected to the end portions thereof, means on alternate of said transverse bars securing slats thereto, a supporting member mounted on said brackets and tiltingly securing said collapsible structure thereto, means associated with said roller and the lowermost of said transverse bars whereby the lowermost bar may be moved upwardly to effect the sequential collapsing of said rigid links and consequently decrease the spacing between said bars and slats thus collapsing the slats, said slat securing means comprising slat receiving arms rigidly attached to the ends of said bars.

5. A Venetian blind having a pair of collapsible

structures supporting the slats in vertically spaced alignment, said collapsible structures each including a plurality of vertically spaced, parallel, transverse bars terminating in laterally extending end portions, alternate bars having arms rigidly mounted on one end thereof to which the slats are secured, vertically disposed, parallel links spacing said bars and pivotally connected to the end portions thereof, cords secured to the lowermost transverse bar of each collapsible structure, cord operating means on said blind whereby the cord may be actuated to raise the lowermost transverse bar whereby the links spacing the bars are pivoted about the ends thereof thus collapsing the structure.

6. A Venetian blind comprising supporting brackets, a spring actuated roller rotatably journaled on said brackets, a pair of collapsible structures supporting the slats in vertically spaced alignment, said collapsible structures each including a plurality of vertically spaced, parallel, transverse bars terminating in laterally extending end portions, alternate bars having arms rigidly mounted on one end thereof to which the slats are secured, vertically disposed, parallel links spacing said bars and pivotally connected to the end portions thereof, cords secured to the lowermost transverse bar of each collapsible structure, said cords being guidingly received by said arms and attached to said roller whereby upon actuation of the roller the cord will be raised consequently pivoting the links about the ends of the transverse bars thus collapsing the bars and slats connected thereto.

7. The combination of claim 6 wherein said slat securing arms each comprises a pair of angularly related arms complementally slotted for guidingly receiving said cord.

8. A collapsible structure for a Venetian blind comprising a plurality of interconnected collapsible sections, each collapsible section including upper and lower transverse bars terminating in laterally extending sleeve ends, vertically extending links terminating in eyelets, pins pivotally interconnecting said eyelets to said sleeve ends, alternate transverse bars having slat receiving arms rigidly secured to an end thereof.
